UNITED STATES PATENT OFFICE.

HARRISON D. MCFADDIN, OF EAST ORANGE, NEW JERSEY.

DESIGN FOR A LAMP-SHADE.

SPECIFICATION forming part of Design No. 35,426, dated December 10, 1901.

Application filed August 24, 1901. Serial No. 73,212. Term of patent 7 years.

To all whom it may concern:

Be it known that I, HARRISON D. MCFADDIN, a citizen of the United States, and a resident of East Orange, in the county of Essex and State of New Jersey, have invented and produced a new and original Design for a Lamp-Shade, of which the following is a full, clear, and exact description.

Reference is to be had to the accompanying drawing, forming a part of this specification, in which the figure is a perspective view of a lamp-shade, showing my design.

My design for a lamp-shade consists in the flaring body 3, having bands 1 2 at the top and bottom, between which the body has a plaited effect, the top and bottom bands being connected at intervals by straps which give the complete shade a paneled effect, as

the bands and straps are on the outer side of the body, and the upper ends of the straps 20 are extended above the upper band, while their lower ends are extended below the bottom band.

Having thus described my invention, I claim as new and desire to secure by Letters 25 Patent—

The design for a lamp-shade, as herein shown and described.

In testimony whereof I have signed my name to this specification in the presence of 30 two subscribing witnesses.

HARRISON D. MCFADDIN.

Witnesses:

EVERARD B. MARSHALL,
WALTON HARRISON.
